UNITED STATES PATENT OFFICE.

EZRA S. BUCKNAM, OF PHILADELPHIA, PENNSYLVANIA, ASSIGNOR TO THE J. G. BRILL CO., OF PHILADELPHIA, PENNSYLVANIA.

CAR.

941,855.

Specification of Letters Patent. Patented Nov. 30, 1909.

Application filed August 12, 1908. Serial No. 448,086.

To all whom it may concern:

Be it known that I, EZRA S. BUCKNAM, a citizen of the United States, and a resident of the city and county of Philadelphia and 5 State of Pennsylvania, have invented a new and useful Improvement in Cars, of which the following is a specification.

The object of my invention is to provide a car with suitable windows, each of which 10 is provided with an upper and a lower sash so arranged and connected that the raising of the lower sash will also raise the upper sash and the two will move together into and out of the roof pockets and also to provide 15 the upper sash with suitable means for permitting it to be lowered so that it will have a certain amount of movement while the lower sash is at rest in its lowest position, so that the window may be opened at 20 the top, a desirable feature in interurban traffic where high speeds are utilized.

This object is accomplished by my invention, one of the embodiments of which is described below.

25 For a more particular description of my invention, reference is to be had to the accompanying drawings, forming a part hereof, in which:

Figure 1 is a sectional view showing a 30 window provided with my improvement. Figs. 2 and 3 are sectional views taken on the lines 2—2 and 3—3 respectively, of Fig. 1. Fig. 4 is an enlarged view of a portion of the structure shown near the line 2—2 of 35 Fig. 1. Fig. 5 is a detailed view showing a portion of the lower sash. Fig. 6 is a sectional view showing a portion of the bottom of the lower sash and the parts adjacent thereto. Fig. 7 shows the pintle in the position 40 it occupies when the sashes are raised into the roof pocket. Fig. 8 is an enlarged detailed view showing the structure near the line 3—3 of Fig. 1.

Throughout the various views of the 45 drawings, similar reference characters designate similar parts.

My improved car window 1 is provided with stanchions 2 connected by the usual window sills 3 and letter board 4, roof 5, 50 deck rail 6, head lining 7, curtain molding 8, as well as the other parts not shown, all of which are of the conventional type, except as hereinafter noted. The stanchions 2 are

also provided with the outside parting strip 9 and the inner parting strip 10, as well as 55 the strip 11 which defines one wall of the curtain groove 12. The stanchions 2 also have a pintle way 13 that extends from the deck rail 6 to or near the window sill 3 and preferably extends substantially as shown 60 in Fig. 1. This pintle way has holes 14 adapted to receive the bolt 15 which is secured near the lower edge of the lower sash 16 in the conventional manner. Below the line 3—3 in Fig. 1 this pintle groove 13 65 curves outwardly and downwardly until in the plane of the sash 16, when it follows the plane of this sash so that the bolt 15 will always rest therein or in the holes 14. This bolt 15 can be withdrawn from the holes 14 70 in the bottom of the groove 13 but not from the groove 13 while the sash 16 is in use so that the sash may be held in any desired position.

The outer edge of the sash 16 is provided 75 with a stop 17 above which is a metal slideway 18 secured to the outer edge of the sash 16 and in this slideway 18 is mounted the upper sash 19 which is so arranged and disposed that it can slide freely in the slideway 80 18 until its movement therein is limited by the stop 17. Near its upper edge, the sash 16 is provided with a pintle 20 which may be of any suitable form but is preferably made as follows. It is provided with a base 85 21 secured to the inside of the sash 16 by screws or other suitable means, and it is provided with a trunnion 22 on which is pivotally mounted a slide 23 which has a large wearing face that rubs against the inner 90 wall of the groove 13 so that this pintle will move over said groove with the least possible friction and wear and tear. The exterior of the sash 16 and immediately below and secured to the top bar 24 thereof is a 95 stop 25 which engages a second stop 26 secured to the upper sash 19 substantially as shown in Fig. 8. The stops 26 and 25 engage to limit the upward movement of the sash 19 while the sash 16 remains at rest and 100 also to cause the lower sash to force the upper sash into its proper position when the window is closed.

The upper edge of the upper sash 19 is provided with a suitable bolt 27 which is 105 adapted to enter holes 28 as shown in dotted

lines in Fig. 4. When the upper sash is so lowered, it slides as stated above in the slide-way 18.

From the foregoing the operation of my improved device will be readily understood. By withdrawing the bolt 15 from its hole 14 and raising the lower sash from the position shown in Fig. 1 in the full lines to the position shown in the dotted lines this sash is raised vertically and the slides 18 engage the sash 19. When the two sashes are abreast they are raised together. When lowered they are also together until the sash 19 is in place when the sash 16 continues its movement alone and the stops 26 and 25 cause the sash 19 to take its proper position when the lower sash 16 is in its proper position and the slide 23 forces the two sashes together so that they are held with a substantially watertight joint. By withdrawing the bolt 27, the sash 19 may be lowered from the position shown in Fig. 1.

While I have shown one embodiment of my invention it is obvious that it is not restricted thereto, but is broad enough to cover all structures that come within the scope of the annexed claims.

What I claim is:

1. In a device of the class described, a pair of stanchions, each of which is provided with a pintle-way, upper and lower sashes adapted to slide between said stanchions, means permitting the upper sash to be lowered while the lower sash is being raised, means for causing the lower sash to either raise or lower the upper sash so that both may be moved together upwardly or downwardly, and pivotally mounted means for automatically causing the upper sash to assume its proper position when the lower sash is down.

2. In a device of the class described, a pair of stanchions each of which is provided with a pintle-way, upper and lower sashes adapted to slide between said stanchions, means for permitting the upper sash to be lowered while the lower sash is being raised, means for causing the lower sash to either raise or lower the upper sash so that both may be moved together upwardly or downwardly, means for allowing the lower sash to continue its movement alone after the upper sash is closed, and pivotally

mounted means for automatically forcing the sashes together when the lower sash is closed.

3. In a device of the class described, a pair of stanchions each of which is provided with a pintle-way, upper and lower sashes adapted to slide between said stanchions, means for permitting the upper sash to be lowered while the lower sash is being raised, means for causing the lower sash to either raise or lower the upper sash so that both may be moved together upwardly or downwardly, means for allowing the lower sash to continue its movement alone after the upper sash is closed, and a pivotally mounted slide on the lower sash for forcing the sashes together when both are closed.

4. In a car of the class described, a window having stanchions at either side, an upper and a lower sash adapted to slide between said stanchions, the lower sash being provided with a stop and a slideway, the upper sash being mounted in said slideway and engageable with said stop, means whereby the upper and lower sash are moved downward together until the upper sash is in closed position and allowing the lower sash to continue its movement alone and rocking means carried by the lower sash for automatically forcing the sashes together when the lower sash reaches its closed position.

5. In a car of the class described, a window having stanchions at either side, an upper and a lower sash adapted to slide between said stanchions, the lower sash being provided with a stop and a slideway, the upper sash being mounted in said slideway and engageable with said stop, means whereby the upper and lower sash are moved downward together until the upper sash is in closed position and allowing the lower sash to continue its movement alone, and pivotally mounted means on the lower sash for forcing the sashes together when the lower sash reaches its closed position.

Signed at the city and county of Philadelphia, State of Pennsylvania, this 10th day of August, 1908.

EZRA S. BUCKNAM.
